UNITED STATES PATENT OFFICE.

ALAN L. BECKET, OF EAST ORANGE, NEW JERSEY.

CARD GAME.

Application filed September 10, 1926. Serial No. 134,610.

My invention relates to card games and in general aims to provide a deck of cards by means of which a game, corresponding to golf in its general range of possibilities and its scoring, may be played by several players.

The feature of the invention lies in the fact that it affords, besides entertainment, a real opportunity for the use of good judgment by the players.

10 The invention will be understood from the description in connection with the accompanying drawings in which Fig. 1 is a view of a single playing hand, and Fig. 2 is a view of 15 a single card. Fig. 3 is a view of a single playing hand at a final stage in the game.

In the drawings, the number shown on the corner of the card in Fig. 2 represents 250 yards or the distance a golf ball may travel 20 after being struck in actual play by a golf club known as a driver. The word Driver shown at the top of the card indicates the type of golf club represented by that particular card and the corner number is the 25 distance in yards allowed, for the purposes of this game, to that golf club on that particular card.

The number shown in the center of the card represents a distance in yards of a golf 30 hole, that distance measured between the tee and the green on the ordinary outdoor golf course.

The game is played by first dealing five cards to each player. The card left on the 35 top of the pack after five cards have been dealt to each player is turned up on the table where it can be seen by everyone. This card shows in the center the distance in yards of the hole being played. Each player tries 40 to equal exactly this distance, by adding together the numbers or distances on the upper left hand corner of the cards in the player's hand. Each player is allowed to discard those cards which he thinks will 45 not finally be used in making up this distance, namely, the distance shown on the center of the card that is turned up on the table. After receiving from the dealer new cards to replace those discarded the player 50 tries to combine cards whose corner numbers or distances when added together will equal exactly the center number or distance shown on the card which has been turned up as described above.

55 I will explain how the hand shown in Fig. 1 is played. Consider Fig. 2 as the card

turned up after dealing. This card designates the distance of the hole to be played as 405 yards. The 250 yard driver card and the 130 yard mashie card, the first and third cards in Fig. 1, will add up to 380 yards which is just 25 yards short of the 405 yard hole, the distance shown on the center of the card turned up Fig. 2. Since the two cards mentioned are the only ones in the 60 hand that the player can use to help make the distance 405 they will be retained and the other three cards will be discarded to be replaced by the dealer with others. The purpose of the discard is to obtain new cards 65 which when added to those retained will equal the required distance. Now consider Fig. 3 as the same hand after the dealer has furnished the player with three new cards to replace those discarded. It is evident 70 that the first four cards in the hand Fig. 3 will total 405 yards or the exact distance of the hole in play. The player accordingly receives a 4 as his score for this hand or hole. Should another player equal 405 yards 75 in three cards, one stroke better than four, then that player would win the hand or in terms of golf would win the hole, provided, of course, that no other player had equaled 80 85 85 with three or less cards.

It is also within the rules of the game to go beyond the hole or the playing distance and return by subtraction i. e., a hole 255 yards long may be played in three cards by combining a 200 yard drive with say a 65 90 yard mashie shot and then subtracting a 10 yard putt from the total of the other two cards.

A game is over after 18 deals or holes have been played. The winner is that player who wins the greatest number of holes. In the event of a tie extra deals or holes are played as in regular golf.

My invention in detail consists of 52 cards including 13 driver cards, 13 mid-iron cards, 13 mashie cards, 13 putter cards. The club distances shown on the corners of the thirteen driver cards are four 300 yards, four 250 yards, five 200 yards and the hole distances or center numbers are; 505, 505, 505, 100 500, 500, 455, 450, 405, 405, 405, 400 yards. The club distances shown on the corners of the thirteen mid-iron cards are; four 180 yards, three 170 yards, three 160 yards, three 150 yards and the hole distances or center numbers are; 455, 455, 455, 445, 445, 435, 105 435, 425, 425, 425, 420, 415, 415 yards. The 110

club distances shown on the corners of the thirteen mashie cards are; 155, 130, 130, 130, 100, 100, 100, 70, 70, 60, 60, 50, 50, and the hole distances or centre numbers are; 5 415, 415, 415, 405, 405, 405, 305, 305, 305, 305, 305. The club distances shown on the corners of the thirteen putter cards are; two 15 yards, five 10 yards, six 5 yards and the hole distances or the center numbers are; 10 295, 295, 295, 285, 285, 275, 275, 265, 265, 255, 255, 245, 155. It will be seen that the hole distance or center numbers range for all cards between 505 yards and 155 yards being the usual distance of holes in regular 15 golf.

It is significant that this game offers a remote chance to make "a hole in one", as the expression goes in golf. This is possible on account of one of the cards being 20 155 yards for the length of the hole and another card bearing a distance of 155 yards for the distance of the club, therefore, any player having the latter in his hand, when the former is turned up after dealing makes 25 a hole in one.

Having thus described my invention it is quite obvious that various immaterial modifications may be made in the same without departing from the spirit of my invention.

30 I claim:

1. A game of the character described, a deck of cards on the faces of which are designated the names of golf clubs, the distances of shots and the distances of golf holes.

35

2. A game of the character described, a deck of cards, said cards bearing the names of golf clubs and numbers representing the distances of golf shots and golf holes.

3. A game of the character described, a 40 deck of cards bearing on the faces thereof names of golf clubs in combination with numbers representing distances in yards attributable to said golf clubs and a number representing in respect to distances a golf 45 hole.

4. A golf card game comprising a pack of cards in which each card has on its face a designation corresponding to a particular kind of stroke in golf, together with a designation corresponding to common distances 50 of golf holes.

50

5. A deck of playing cards comprising 52 cards, each card bearing the name of a golf club together with a number corresponding to a distance common to a stroke as in golf and a number corresponding to a distance common to an actual golf hole.

55
